P. ORSI

TIE HOLDER

Filed Jan. 4, 1922

INVENTOR

PETER ORSI

By Chas. E. Jansen
ATTY.

UNITED STATES PATENT OFFICE.

PETER ORSI, OF STOCKTON, CALIFORNIA.

TIE HOLDER.

Application filed January 4, 1922. Serial No. 526,389.

To all whom it may concern:

Be it known that I, PETER ORSI, a citizen of the United States, residing at Stockton, in the county of San Joaquin and State of California, have invented new and useful Improvements in Tie Holders, of which the following is a specification.

This invention relates to a tie holder, and particularly pertains to a support for 10 tailor-made ties.

It is the principal object of the present invention to provide a tie holder upon which tailor-made ties may be secured and easily detached, said holder being so designed as to satisfactorily secure the holder to the button of a collar and at the same time to engage the outer folds of a collar to hold the tie in position and to conceal the support therefor.

20 The present invention contemplates a structure adapted particularly for use with turn-over collars, and comprises a rigid back plate carrying a yieldable button clip, the back plate being further fitted with resilient fingers adapted to engage and grip the opposite flaps of a collar and carrying a pin or clasp for detachably securing a tie to the plate.

25 The invention is illustrated by way of example in the accompanying drawing, in which:

Figure 1 is a view in elevation showing the application of the present invention.

Fig. 2 is a view in perspective showing the complete structure of the holder as seen from in front.

Fig. 3 is a view in elevation showing the back of the holder.

Fig. 4 is a view in plan showing the relation of the various parts of the holder to a collar and its button.

Referring more particularly to the drawings, 10 indicates a collar. This is shown as the conventional turn-over collar secured 45 to a collar band by a button in the rear and a button 11 in front. 12 indicates the tie holder. This holder is formed with a substantially rigid back plate 13. The back plate 13 is preferably made of textile material which, while possessing considerable rigidity, might be readily altered to conform to different sizes of collars. The back plate 13 is formed with two oppositely extending wings which lie between the front 50 and rear folds of the collar. Secured in-

termediate the ends of the wings and to the front wings of the plate are a pair of yieldable fingers 14. These fingers frictionally engage the front flaps of the collar and cooperate with the back plate to firmly hold the tie-supporting structure in position. The holding of the structure is further insured by a button clip 16. This clip is secured upon the opposite side of the plate 13 and comprises a member fastened by its opposite ends to the plate and having a central yieldable section formed with a slotted opening 17. This opening has a narrow throat at its lower end which communicates with a larger circular opening. 70

The wing portions 13 of the plate form a continuation of the central enlarged portion which projects downwardly, as indicated at 18. This part of the plate carries a pin 19. The pin is hinged at one end and 75 has a clamp at its opposite end for holding a tie 20 in position thereon.

In the operation of the present invention the tie 20 is made up in any suitable manner, preferably by taking the various folds 80 forming the tie wing and throwing a knot across them to resemble the usual bow tie. It will also be understood that a four-in-hand tie may be utilized, if desired, to provide a four-in-hand which is secured by the pin 19 to the plate. The tie may then be placed in position by first putting the collar on and securing it by the front button 11, after which the back plate is inserted between the front and rear folds of the collar 85 and the clip 16 passed down over the collar button. The spring fingers 14 will extend over the front flap of the collar and tend to hold the form in its proper position. This feature of the invention is also quite desirable when soft 90 collars are used, as it will act to hold the collar snugly around the neck and prevent it from sagging in front.

It will thus be seen that the tie-holder here disclosed, while simple in construction, provides a suitable detachable support for any type of tie and insures that it may readily and easily be held in position upon a collar. 100

While I have shown the preferred form of my invention as now known to me, I wish it understood that various changes in the combination, construction and arrangement of parts may be made by those skilled in the 110

art without departing from the spirit of my invention as disclosed in the appended claims.

Having thus described my invention, 5 what I claim and desire to secure by Letters Patent is:

1. A necktie holder comprising a frame bar, an inwardly projecting member mounted on the inner side thereof and having a 10 slot therein for engaging a collar button, a fastening element secured to the outer side of the frame bar for detachably connecting a tie thereto, and spring fingers arranged on the outer side of the frame bar to engage 15 the collar and secure the device in a proper position thereon.

2. A necktie holder comprising an elongated arcuate frame bar, an inwardly projecting lug having a slot therein arranged on 20 the inner side of the frame bar to engage a collar button, a pair of spring fingers arranged on the opposite side of the frame bar and parallel thereto to engage the outer

fold of a collar for firmly maintaining the device in position relatively to a collar, and 25 a fastening element mounted on the frame bar for engaging a necktie and detachably securing the same thereon.

3. As an article of manufacture, a necktie holder comprising an elongated arcuate 30 frame bar, an inwardly projecting lug secured centrally on the inner side of the frame and having a slot therein for engaging a collar button, a pair of curved spring fingers secured on the outermost side of 35 the frame bar and extending parallel thereto for engaging the outer fold of a collar and clamping the same between the frame bar, and the said fingers for maintaining the device in correct position relatively to 40 the collar, and a fastener element secured to the outermost side of the frame bar and adapted to engage a necktie and detachably mount the same on the frame bar.

PETER ORSI.
